METHOD OF FORMING LINER PLATES

Pearson M. Payne, Denver, Colo.

Application April 28, 1938, Serial No. 204,714

4 Claims. (Cl. 29—188)

This invention relates to grinding and comminuting mills, and more particularly to the abrasive resisting inner surfaces of such mills, and has as an object to provide improved liner means 5 adapted for removable and replaceable association with the inner surfaces of such mills.

A further object of the invention is to provide an improved construction for mill liner sections or plates.

10 A further object of the invention is to provide an improved combination of a highly abrasive-resisting, hard, and consequently brittle grinding section with a relatively softer and more elastic supporting member in a manner constituting a mill liner section or plate.

15 A further object of the invention is to provide improved means for interconnecting a hard and brittle wearing section with a relatively softer and less brittle backing element to form a mill liner section or plate.

20 A further object of the invention is to provide as units of manufacture and replacement, mill liner sections or plates in the form of a unitary combination of a grinding section with a relatively- 25 ly softer and less brittle backing element.

25 A further object of the invention is to provide an improved method for the manufacture and production of mill liner sections or plates.

30 A further object of the invention is to provide an improved method for the manufacture and production of unitary combinations of a wearing section with a relatively softer and less brittle backing element for use with high efficiency and enhanced advantage as mill liner sections or 35 plates.

35 A further object of the invention is to provide an improved composite mill liner section or plate which is free from many of the disadvantages of functionally similar conventional constructions, 40 which permits of the practical and efficient use of very hard, highly abrasive-resisting material as a wearing base and section, which is susceptible of simple and convenient construction through the use of conventional apparatus in sizes and shapes adapted for operative association with conventional mills, and which presents advantages of greater operative durability and longer efficient life in comparison with conventional like 45 units.

50 My invention consists in the construction, arrangement, and combination of elements, and in the method employed in effecting a unitary combination of such elements, as hereinafter set forth, pointed out in my claims, and illustrated 55 by the accompanying drawing, in which—

Figure 1 is an elevation of the outer or contacting side of a mill liner section embodying the principles of my invention. Figure 2 is a longitudinal section taken on the indicated line 2—2 of Figure 1. Figure 3 is a transverse section taken on the indicated line 3—3 of Figure 1 and illustrating the assembly of said latter figure in operative association with a portion of a mill shell and with the immediately adjacent, complementary liner sections. Figure 4 is a fragmentary, detail section illustrating alternative means employable in giving effect to my invention. Figures 5, 6, and 7 are views similar to Figure 4, illustrating various alternative means employable in the practical development and use of the invention.

Conventional construction of ball and rod mills employed in the grinding and comminution of ores and similar materials includes a substantially cylindrical, hollow shell, mounted for rotation about its axis and lined with removable and replaceable sections or plates of wear resisting material rigidly clamped to said shell for rotation therewith, the interior of the drum thus formed being supplied with a quantity of loosely disposed balls or rods which cascade and roll about within the mill for impact and grinding effect on material fed into said drum. The liner sections or plates must resist the abrasive action of the material to be ground and must withstand, as well, impact effect of the grinding balls and rods. Low-cost metals in cast form, particularly white iron, are characterized by relatively extreme hardness and high resistance to abrasion, and hence are, from the stand-point of economy and efficient grinding, highly desirable for use in the construction of mill liner sections and plates, but such materials are characterized by very low elasticity and are consequently relatively very brittle, which is a notable disadvantage in that liner sections or plates of such material are frequently broken in handling, transit, and installation.

The brittle character of the hard liner sections and plates is of further disadvantage in that it permits fracturing and ultimate destructive disintegration of such plates under impact in use, particularly when the plate has been worn down in thickness, so that the initial relatively lower cost of the liner installation may be offset by the necessity for frequent renewal of the liner plates. Relatively more elastic and less brittle liner units may be formed from more expensive materials and alloys, but the gain in strength and durability of units so manufactured is at least partial.

ly offset by loss of hardness and consequent wearing efficiency, hence a liner construction wherein the wear resistance and long life of white iron or other hard material may be combined in a unit 5 having the strength and operative durability of the less brittle materials presents practical advantage of both initial and operative economy and constitutes a long-sought contribution to the art of comminuting and grinding.

10 The instant invention is concerned with the provision of a liner plate or section wherein a relatively thicker wearing portion of white iron or equivalent metal is rigidly and permanently attached to a backing plate having a relatively 15 high coefficient of elasticity, to form a liner section or plate adapted for removable and replaceable association with a mill shell and for marginally adjacent cooperation with other such units to cover the inner cylindrical surfaces of 20 such shell. As shown in the drawing, the numeral 10 designates the inside body portion of the improved unit, which portion is formed by casting or molding of highly abrasive-resisting hard material such as white iron, to a length and 25 width corresponding to the conventional sizes used in the grinding chamber of a mill wherein with the unit is to be associated, with substantially arcuate, concentric inner and outer surfaces adapted to cooperate with the curvature of 30 the mill drum, and with long side margins defined by converging planes corresponding with radii of the mill, all of which is in itself conventional and well-known practice. The inner or 35 wearing face of the portion 10 may be formed with a longitudinal rib 11, or such other protuberance, depressions, or deformations as may be deemed best suited to comminution of a given material in a specific mill, and said portion 10, including in this instance the rib 11, is intersected by suitable, spaced, radially-traversing 40 bores 12 extending entirely through said portion for registration with corresponding holes in a mill shell to provide means for securely bolting the liner unit to said shell. The bores 12 may 45 vary in specific form and arrangement as may be deemed most expedient for a given installation, the arrangement shown in the drawing contem- 50 plating an elongated oval recess with its greater axis directed longitudinally of the unit and opening through the grinding face of the latter to receive the oval head portion of a bolt 13, an 55 outwardly-converging bore portion continuing said oval recess and adapted to seat against and receive pressure from a tapered neck portion of the bolt 13, and an extension of said tapered portion opening through the outer wall of the casting 10 to receive the shank of said bolt 13, so that 60 when a nut 14 is tightened on the bolt 13 against the outer surface of a mill shell 15, the tapered neck of said bolt acts against the tapered portion of the bore 12 to closely and firmly clamp the liner 10 against the mill shell. The clamping means shown and described is typical of such 65 means commonly employed and is in itself productive of fractures in simple white iron liner castings due to the fact that the outer surfaces of said castings can not always conform exactly with inner surfaces of the mill shell against which they are to be clamped, and the brittle character 70 of the white iron material can not yield without fracture to the clamping effect applied through the bolts 13 when the latter are tightened against the shell 15.

In giving effect to the instant invention, the 75 liner portion 10 is associated with and firmly and

permanently secured to a relatively thin backing plate 16 of a material relatively softer and less brittle than the white iron of the casting 10, the backing plate 16 being conveniently formed of sheet steel, or equivalent material, which has the 5 characteristics noted. The backing plate 16 is formed to a length corresponding with that of the casting 10, to a curvature concentric with and adapted to fit closely between the outer surface of the casting 10 and the inner surface of 10 the mill shell 15, and has a width defined by the same radial planes as limit and define the long margins of the casting. To secure the plate 16 to and in the desired relation with the casting 10, said plate is formed with a plurality of identical 15 holes or openings 17 disposed throughout its surface area in relatively closely spaced arrangement and in conformity with a definite, predetermined pattern, other holes 18 being formed through the plate 16 in position to register with 20 and continue adjacent portions of the bores 12 for accommodation of the shank of the bolt 13. The holes 17 conform in pattern with an arrangement of studs, inserts, pins, or rivets 19 imbedded in the outer surface of the casting 10 25 at the time the latter is cast, and projecting from said outer surface of the casting a distance somewhat less than the thickness of the backing plate 16. It is, in a practical sense, immaterial whether the elements 19 have headed portions imbedded 30 in the metal of the casting 10, as shown, or whether said elements are simply straight studs or pins, since the casting of the metal 10 about said elements will provide a bond sufficient to hold the elements 19 firmly to said casting 35 against any pressures which may act to effect a separation therebetween. The elements 19 are of a metal susceptible to welding, riveting, and like treatment, and are preferably of soft steel 40 or equivalent material. With the elements 19 dis- 45 posed in the casting 10 to conform with the pattern of the holes 17 and arranged to project from their casting a distance less than the thickness of the backing plate 16, it is desirable that the holes 17 have a diameter somewhat in ex- 50 cess of the diameter of the elements 19 to be received therein, which variation of diameter has a two-fold function in that it permits accommoda- 55 tion of slight variations and inaccuracies in the registration of the elements 19 with the holes 50 17, and leaves a space or clearance about each element 19 within its respective hole 17 which may be filled by welding to securely fasten the projecting portion of each element 19 within and to its corresponding hole 17. As is clearly shown 55 in the first three figures of the drawing, the backing plate 16 is positioned closely against the outer surface of the casting 10 with the projecting portions of the elements 19 received in correspond- 60 ing holes 17, whereafter each of said elements is 65 securely brazed or welded to adjacent margins of its hole 17, the relative short projection of the elements 19 and the clearance between each element 19 and its corresponding hole 17 permitting the formation of a strong welded bond there- 70 between without the necessity of marring or de- 75 forming in any way the outer surface of the backing plate 16 which is adapted to seat against the inner curvature of the shell 15.

While it is believed that considerations of 70 economy and practicality are best served by fixing the backing plate to the casting 10 in the manner just above described, alternative means for the same purpose are available as indicated in Figures 4 to 7, inclusive. In Figure 4 is illustrated an 75

arrangement wherein the holes 17 are tapered inwardly toward the wearing face of the casting 10, as indicated at 17', and the elements 19 are replaced by elements 19' having a projecting length greater than the thickness of the backing plate 16, in which arrangement the projecting portions of the elements 19' are designed to be upset or riveted into an expanded relation closely filling the frusto-conical holes 17', thus uniting the casting 10 and back plate 16 in a unitary assembly.

The showing of Figure 6 is closely analogous to that of Figure 4, the elements 19' being replaced by a short stud 20, of soft metal, which terminates flush with the surface of the casting 10, a frusto-conical cap member 21 being seated in the tapered holes 17' in registration with the exposed end of the stud 20 to which said cap 21 is butt-welded to establish the desired connection between the casting 10 and backing plate 17.

In the modification according to Figure 5, the backing plate 16 is provided with tapered holes 17' adapted to register with openings in the casting 10 which communicate with the threaded holes or nuts 22 embedded in said casting, so that conical-head screws 23 may threadedly engage the nuts 22 with their heads seated and bearing against the holes 17' to firmly clamp the backing plate to the casting.

In Figure 7 an arrangement is shown wherein threaded bolts 24 are positioned with their heads embedded in the casting 10 and their threaded stem portions projecting beyond the outer surface of said casting a distance less than the thickness of the backing plate 16, for threaded engagement with nuts 25 adapted to be received in counter bores 26 formed in the outer surface of the plate 16 in concentric relation with the hole formed in said backing plate for reception of the bolt stem.

The improved liner plate constructed as shown and described provides a wearing portion of low cost material which is very hard and highly efficient, in combination with a supporting or backing plate so associated with the abrasive-resisting liner portion as to position and hold the latter against destructive disintegration even after the wearing portion has been extensively fractured as a result of mounting strains and impact effects. The clamping action of the bolts 13 in the construction shown is had against shoulders formed in the casting 10, rather than against the backing plate 16, so there is no tendency for said plate 16 to be pulled away from the casting 10, said plate 16 serving rather as a bridge to connect and hold the portions of the casting 10 in the desired operative relation for continued wearing action until such portions have been worn so thin as to preclude further effective gripping thereof by the elements interconnecting between the casting and the backing plate. As is the case with conventional liner installations, a loose condition of a liner mounting which necessitates tightening of the clamp bolts

is indicated by leakage of fines outwardly of the mill shell about those bolts 13 which are loose, and a condition of wear of the improved liner plate construction which necessitates replacement of the liner assembly is indicated by the presence of chips or relatively small pieces of material from the casting 10 in the discharge from the mill, such indications evidencing wear of the liner plates to a thickness less than will permit the interconnecting elements to continue to long hold the casting portions to their backing plate.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention—

1. The method of forming mill liner plates which consists of casting a wearing section from hard, highly abrasive-resisting material, providing said wearing section with rigidly-held attaching lugs of more ductile material embedded therein at the time of molding to project from its outer surface, and rigidly connecting a coextensive backing plate of non-brittle material formed with holes disposed to receive said lugs to said lugs in closely-overlying relation with said wearing section outer surface.

2. The method of forming mill liner plates which consists of casting a wearing section of hard, highly abrasive-resisting material, coincidentally embedding lugs of more ductile material in said casting in spaced relation on and projecting from the outer surface of said casting, forming a coextensive backing plate of non-brittle material with holes to receive said lugs and closely overlie said casting outer surface, and rigidly interconnecting said lugs with adjacent portions of said backing plate.

3. The method of forming mill liner plates which consists of casting a white iron wearing section, coincidentally embedding relatively more ductile lugs in said casting in spaced relation on and projecting from said casting outer surface, forming a coextensive steel plate to closely overlie said casting outer surface and with holes adapted to receive said lugs, and welding said lugs to adjacent portions of said backing plate.

4. The method of forming mill liner plates which consists of rigidly interconnecting a backing plate of non-brittle material closely against and in coextensive covering relation with the outer surface of a highly abrasive-resisting casting by embedding ductile lugs at the time of molding in said casting to project from said casting outer surface, forming holes in said plate disposed to receive said lugs, and rigidly interconnecting said lugs and plate.
